PERFUME OILS CONTAINING 3-METHYL-1-NONYN-3-OL

Thomas F. Wood, Little Falls, N.J., assignor to The Givaudan Corporation, New York, N.Y., a corporation of New Jersey

No Drawing. Application November 9, 1955
Serial No. 546,005

1 Claim. (Cl. 167—94)

This invention relates to perfume-containing compositions, and more especially to such compositions as cosmetic creams, detergent soaps, perfume oils and the like, which contain 3-methyl-1-nonyn-3-ol.

As is well known, many ingredients used in perfumery have natural origins, i.e., they are obtained from a natural source. In many cases the source is a distant one. As a result, the products obtained from such sources are often characterized by non-uniformity as regards not only composition but also as regards prices, which fluctuate over wide ranges, and availability, which is affected by political upheavals and local and general wars. An example of a widely-used perfume ingredient which has a natural source is linalool.

An object of this invention is to provide a synthetic substitute for the naturally-occurring linalool. A further object is to provide replacement for linalool which has desirable olfactory properties and at the same time can be made at a relatively inexpensive cost and in ample amounts. Other objects of this invention will be apparent from the following description.

In accordance with my invention I utilize 3-methyl-1-nonyn-3-ol as an olfactory ingredient in perfume-containing compositions such as cosmetic creams, detergent soaps, perfume oils and the like. The term "perfume-containing compositions" herein is intended to mean perfume oils, cosmetic creams and detergent soap.

The amounts of 3-methyl-1-nonyn-3-ol employed differ according to the desires of the compounder and the nature of the composition. For purposes of illustration it has been found that, in general, a cosmetic cream having from about 0.01 to about 0.8 percent by weight of 3-methyl-1-nonyn-3-ol on the weight of the finished cream gives satisfactory results, amounts from about 0.1% to about 0.3% being especially satisfactory. Detergent soaps having from about 0.01 to about 0.5 percent by weight of 3-methyl-1-nonyn-3-ol on the weight of the finished bar of soap give desirable results, amounts from about 0.1 to about 0.2 percent giving especially desirable results. Perfume oils having from about 1.0 to about 80 percent of 3-methyl-1-nonyn-3-ol on the weight formula total are satisfactory, amounts from about 20 to about 50 percent being recommended in general.

The novel perfume ingredient herein-disclosed has been described in the scientific literature. In this connection reference is made to the following citations for methods of preparing the 3-methyl-1-nonyn-3-ol: Compt. rend., 234, 1557-9 (1952); J.A.C.S., 69, 239-41 (1947); and U.S. Patent 2,385,547.

The novel ingredient for the purposes of this invention may be incorporated in perfume-containing compositions in the conventional manner and hence no special directions are thought to be necessary here.

The compositions containing 3-methyl-1-nonyn-3-ol have imparted to them a light, highly-diffusing floral character without any resultant discoloration being caused by the 3-methyl-1-nonyn-3-ol.

In order further to clarify my invention, the following

2

examples are given, it being understood that they are for purposes of illustration and not for purposes of limitation.

Example I

5 0.2 gram of 3-methyl-1-nonyn-3-ol was incorporated into 20.0 grams of white milled toilet soap by weighing the soap and 3-methyl-1-nonyn-3-ol, milling them together in a porcelain mortar until they are intimately combined, adding to them 2.0 gms. of distilled water, further milling 10 until the mixture has a homogeneous plastic consistency and then compressing this mass into a soap cake by means of a stainless steel tablet-forming die and a hand arbor press.

The soap had a light but fresh floral odor which remained stable for more than 10 months exposed to air and daylight. The color of the soap also remained the same throughout this 10 month period.

Example II

20 A cosmetic cream was made by melting 12 grams of beeswax in 46 grams of mineral oil. Forty grams of a solution of 1 gram of borax in 39 grams of water were added slowly to the beeswax-mineral oil melt. The mixture was stirred continuously while being allowed to cool to 50° C.

25 1.0 gram of 3-methyl-1-nonyn-3-ol was added to this cream which was stirred until the 3-methyl-1-nonyn-3-ol was intimately combined with it.

The resulting cream was cooled to room temperature 30 and was found to have a stable light floral odor. The cream did not discolor upon standing at room temperature for 10 months.

Example III

35 A perfume oil having a jasmin character was made by mixing together the following ingredients in the amounts given:

	Grams
3-methyl-1-nonyn-3-ol	100
Benzyl acetate	200
Amyl cinnamic aldehyde	28
Phenyl ethyl alcohol	100
Hydroxy citronellal	200
Phenoxy ethyl iso butyrate	80
45 p-Cresyl phenyl acetate	28
Indole 1% in benzyl benzoate	22
Phenyl acetaldehyde 50%	10
Cedryl acetate distilled	8
Naphthalene	6
50 N-decanal 10% diethyl phthalate	1
Phenyl propyl aldehyde	2
Oil cade	3
Oil peppermint	2
Oil thyme red	3
Oil cedarleaf	3
Soluble resin galbanum	2

Example IV

60 A perfume oil having a honeysuckle character was made by mixing together the following ingredients in the amounts given:

	Grams
3-methyl-1-nonyn-3-ol	280
Benzyl acetate	200
Phenyl ethyl iso butyrate	120
Amyl cinnamic aldehyde	40
Benzyl iso amyl ether	52
65 p-Cresyl phenyl acetate	8
Cyclamen aldehyde	4
Hydroxy citronellal	20
Lauric aldehyde	1
Indole 1% in benzyl benzoate	3

Phenyl acetaldehyde 50%	Grams
Phenyl acetic acid	6
Oil petitgrain	4
Soluble resin olibanum	18
Geranium bourbon	6
Methyl anthranilate	5
Cedrenol	7
Vanillin	2
Oil red thyme	2

Example V

A perfume oil having a rose character was made by mixing together the following ingredients in the amounts given:

3-methyl-1-nonyl-3-ol	Grams
Geraniol pure	180
Phenyl ethyl alcohol	260
Benzyl acetate	120
Cyclamen aldehyde	60
Ionone alpha white	20
Musk ketone	8
Undecylenic aldehyde 10% in diethyl phthalate	4
Phenyl acetaldehyde 50%	4
Oil bay	2
Methyl acetophenone	25
Oil star anise	8
Oil lavender 38/40	1

Example VI

A perfume oil having an orange blossom character was made by mixing together the following ingredients in the amounts given:

3-methyl-1-nonyl-3-ol	Grams
Nerol	200
Phenyl ethyl alcohol	120
Hydroxy citronellal	80
Methyl anthranilate	40
Amyl benzoate	46
Oil bergamot	40
Geranyl formate	32
Benzyl acetate	40
Indole	20
Phenyl acetic acid	45
N-decanal 10% in diethyl phthalate	4
Oil estragon	4
Soluble resin balsam Peru	4
Methyl acetophenone	4
Oil peppermint	2
Oil Caraway	3
Oil cade	1
Oil citronella-ceylon	1

Example VII

A perfume oil having a lilac character was made by mixing together the following ingredients in the amounts given:

3-methyl-1-nonyl-3-ol	Grams
Heliotropin	400
Benzyl acetate	160
Anisic acetate	160
Anisic aldehyde	60
Methyl acetophenone	65
Hydroxy citronellal	20
Phenyl propyl aldehyde	20
Isopropyl quinolene 10% in benzyl benzoate	20
Phenyl ethyl alcohol	48
Methyl nonyl acetaldehyde 10% in diethyl phthalate	20
Skatole 10% in diethyl phthalate	11
p-Cresol 10% in benzyl benzoate	70

Undecalactone	Grams
Oil spearmint	2
Soluble resin galbanum	8
Oil patchouly	1
Oil nutmeg	3
Pine needle Siberian	3
Oil cade 5% in alcohol	4

Example VIII

A perfume oil having the character of coriander oil was made by mixing together the following ingredients in the amounts given:

3-methyl-1-nonyl-3-ol	Grams
p-Cymene	520
Phellandrene	80
N-decanal	24
Borneol technical	4
Benzyl iso amyl ether	8
N-nonal	8
Furfuryl acetate	6
Oil star anise	5
Siberian pine needles	3
Citronella Ceylon	3
Oil cumin	2
Coumarin	2

Example IX

A perfume oil having the character of cinnamon oil was made by mixing together the following ingredients in the amounts given:

3-methyl-1-nonyl-3-ol	Grams
Cinnamic aldehyde	280
p-Cymene	380
L-phellandrene	20
N-nonal	40
Phenyl propyl aldehyde	1
Furfural technical	3
Methyl amyl ketone	2
Benzaldehyde	16
Coumarin 10% in diethyl phthalate	2
Oil clove bud	2
Soluble resin olibanum	3
Oil peppermint	3
Oil rosemary	2

Example X

A perfume oil having the character of Bois de Rose oil was made by mixing together the following ingredients in the amounts given:

3-methyl-1-nonyl-3-ol	Grams
Terpineol	2600
Myrcene	200
Terpinolene	85
Dipentene	50
p-Methyl acetophenone	50
Geraniol	10
Furfural	31
Resin olibanum	5
Oil spike lavender	15
Oil peppermint	15
Oil lemongrass native	25
Oil rue	20

While I have described my invention in detail in its preferred embodiments, it will be obvious to those skilled in the art that various changes and modifications may be made therein, in particular in the actual formulations employed, without departing from the spirit or scope thereof. I aim in the appended claim to cover all such modifications and changes.

I claim:

A perfume oil having 3-methyl-1-nonyl-3-ol as an olfactory ingredient.
